UNITED STATES PATENT OFFICE.

HORACE E. SMYTHE, OF OAKMONT, PENNSYLVANIA.

GAS-PRODUCER.

No. 879,920.

Specification of Letters Patent.

Patented Feb. 25, 1908.

Application filed February 18, 1907. Serial No. 358,026.

To all whom it may concern:

Be it known that I, HORACE E. SMYTHE, residing at Oakmont, in the county of Allegheny and State of Pennsylvania, a citizen of the United States, have invented or discovered certain new and useful Improvements in Gas-Producers, of which improvement the following is a specification.

It is incident to the operation of gas producers that the charge becomes so packed and wedged therein that when the ashes are removed from the lower part, the charge will not fall down but will remain suspended and it must be broken up more or less by pokers inserted through holes in the top, not only to break up the charge but also to remove any portions adhering to the walls of the producer. This difficulty is especially incident to the operation of gas producers having water seals and is objectionable for the reason that the holes made by the pokers will permit the air and steam forced in with the blast, to pass up and ignite the gas in the upper part of the chamber.

The present invention has for its object the breaking up of the charge in the furnace or a portion thereof from below at the time the ashes are removed, so that the weight of the upper portion of the charge will destroy any adhesion to the sides of the furnace and permit the charge to drop down without any material breaking up.

The invention is hereinafter more fully described and claimed.

In the accompanying drawings forming a part of this specification, Figure 1 is a sectional elevation of a water sealed gas producer having my improvement applied thereto. Fig. 2 is a similar view on a plane at right angles to that shown in Fig. 1. Fig. 3 is a sectional plan view on a plane indicated by the line III—III Fig. 1. Fig. 4 is a sectional view similar to Fig. 2 illustrating a modification of my improvement. Fig. 5 is a similar view on a plane at right angles to Fig. 4; and Fig. 6 is a sectional plan view on a plane indicated by the line III—III Fig. 4.

In the practice of my invention, the body of the producer 1 is supported upon suitable side piers 2 and the mantle plates 3 which in turn are supported by the piers or abutments. The interior of the producer is in communication through the openings 4 below the mantle plates with the basins 5 at the sides of the furnace. These mantle plates are below the level of the water contained in

these basins, so that the water forms a perfect seal and the ashes, etc., can be removed from the producer through the openings 4 into the basins, whence they are to be withdrawn by a rake or other suitable means. As is customary in the operation of water sealed producers, the charge within the producer is supported by the ashes, etc., resting on the bottom plate 6, no grate being employed. As these ashes are removed the charge will gradually settle, provided it does not arch over or does not adhere too tightly to the sides of the producer.

As hereinbefore stated a poker is used in case of the failure of the discharge to descend from either of the causes stated to break up the arch or loosen the adhering portions from the sides of the furnace. To avoid the use of pokers and the consequent formation of holes through the upper portion of the charge I provide for a stirring up of the portion of the charge near the lower end of the producer, by means of a series of arms 8, extending radially from a hollow shaft 9, mounted in suitable bearings 10, in the walls of the producer and connected at one end to the blast box 11. These arms as clearly shown in Figs. 1 and 3 are made hollow and provided with perforations for the escape of the blast therefrom. The perforations are protected by hoods 12 which will prevent the entrance of ashes into the openings and clog the same. This shaft may be rotated by any suitable means as for example that shown consisting of a chain 13 passing around a sprocket wheel in the shaft and around a drum 14 suitably arranged at the top of the producer and suitably driven by a crank or handle. After the ashes etc., have been removed from the ash pan or pit, and the charge fails to descend this shaft is rotated and the arms will break up the closely compacted material in the lower portion of the charge so that it will drop, leaving the upper portion unsupported. The weight of this unsupported mass will cause it to descend tearing away any adhering particles from the walls of the producer. This downward movement in mass will not materially disintegrate the charge. This shaft with the radial arms does not in any respect operate as or serve the purpose of a supporting grate, the arms being separated such a distance that they will not present any material obstruction to the usual settling down of the charge into the ash pit.

In the construction shown in Figs. 1 to 3, inclusive, the blast is introduced through the shaft and radial arms. As shown in Figs. 4 to 6 inclusive, this shaft with its arms may be employed simply for loosening the charge and the blast can be introduced through nozzles and connected to the blast supply pipe by vertical pipes 16. As the shaft with its arms is located in a portion of the furnace where it would be subject to considerable heat, provision is made for the circulation of water therethrough, the water being introduced into the interior of the shaft by a pipe 17 and escaping into a box 18 at one end of the shaft, said box having an outlet pipe 19. In addition to the blast introduced by the nozzles it may also be introduced at the same time through blast boxes 20 which are substituted and perform the function of the mantle plates heretofore described.

It will be observed that the arms 8 are so located in the lower portion of the producer that when rotated they will tend to force the ashes down and towards one or the other of the openings in the ash pit from which the ashes are removed.

I claim herein as my invention:

1. A gas producer having in combination means for supporting the charge and means arranged in the producer above and adjacent to the lower portion of and adjacent to the

charge supports and movable in vertical planes for loosening the lower portion of the charge.

2. A gas producer having discharge openings at its lower ends, a basin extending above the upper walls of said openings said basin forming the support for the charge, a shaft horizontally extending across the producer in a plane above and adjacent to the discharge openings and provided with radial arms, and means for rotating the shaft.

3. A water sealed gas producer having in combination therewith, a shaft horizontally extending across the producer in a plane above the water seal and provided with arms, means for rotating the shaft, and means for introducing a blast of air into the producer.

4. A water sealed gas producer having in combination therewith a hollow shaft extending horizontally across the producer in a plane above the water seal and provided with hollow arms having perforations, means for rotating the shaft and means for introducing a blast into said shaft.

In testimony whereof, I have hereunto set my hand.

HORACE E. SMYTHE.
